N°. 995.

*John P. Koch's
Simp^{le} Design for Legs & Posts for Iron Bed stands.*

Patented March 23, 1858.

John P. Koch, of New York, N. Y.
Letters Patent No. 995 - Dated Mar. 23, 1858.

The schedule referred to in these Letters Patent & making part of the same.

To all whom it may concern:

Be it known that I, John P. Koch, of New York, in the county and state of New York, have invented a new and original design for Legs and Posts of Bedsteads, and do hereby declare that the following is a full and exact description of the same. The corner legs of the Bedstead consist of a scroll a, finishing in the figure of a neck & head of a bird (C) with wings of a bird (C) and covered towards the middle by a shell or shield (f). The neck of the bird (C) is twisted & supports ..... together with the ends of the wings (C), a rectilinear capital, g, filled in with scroll work, to which the bottom of B is fastened.

The upright posts are formed of a carved standard (m) resting upon the capital g, and strengthened by a brace (m) running in a graceful curve from the upper end of the standard to the capital g, to which it is joined. This brace (m) is covered with light scroll work (w), the upper end of which represents to bind the top of the standard and of the brace together.

Between the bottom of the standard (m) and the bottom of the brace (m) a praying angel (p) is represented kneeling, supporting on its head the lower part of the above mentioned scroll work (w).

The legs for the center of the Bedstead, are formed of arabesque scroll work (h) supporting an eagle (k) with out-spread wings, having on its head and upon the ends of the wings a capital (g) ornamented with corresponding arabesque scroll work, and characteristic leaves and rosettes.

2

What I claim as my invention & desire to secure by Letters Patent, is, my design for Feet & Posts for Iron Bedsteads, consisting of the described scroll work, standard and Brace with a praying angel kneeling between the latter for the Posts of Iron Bedsteads, and the figure of an Eagle with outspread wings resting upon arabesque scroll work, and carrying a corresponding capital on its head and the ends of the wings for the center feet as represented.

And Witnesses.
